UNITED STATES PATENT OFFICE.

THEODORE A. SCHRAISHUHN, OF CORAOPOLIS, PENNSYLVANIA, ASSIGNOR TO LEWIS
FOUNDRY & MACHINE COMPANY, A CORPORATION OF PENNSYLVANIA.

ROLLING MILL.

Application filed July 23, 1926. Serial No. 124,349.

This invention relates to a rolling mill, and particularly to a mill for the cold forming of metallic shapes by bending the stock metal.

5 A mill of the type noted is operated as a continuous mill the stock being progressively formed in the successive passes of the mill. For various classes of work it is therefore desirable that a mill comprise 10 a greater number of pairs of die spindles than is necessary for other classes of work. For this reason it is of advantage that the general arrangement of the mill be by units, so that a greater or lesser number of die 15 spindles may be provided in a machine without alteration in the fundamental design of the machine as a whole, and that a manufactured machine may be adapted to various classes of work by the addition or 20 removal of a unit or units.

One object of the invention is to provide a forming mill in which compact driving connections are employed to actuate all of the units of the mill from a common driving shaft.

25 Another object of the invention is to so arrange the driving connections and housings of each unit that the die spindles of the units are held against horizontal movement in one direction, and relative displacement of the driving gears avoided, without the provision of locking collars or similar fastening means.

30 A closely related object of the invention is to provide for the ready lateral adjustment of one housing of each unit to position the forming dies on their shafts without the use of spacing collars or other spacing means.

35 Another object of the invention is to provide a forming mill of unit construction so arranged as to allow space between adjacent pairs of spindles for the insertion of side dies or guides of any desired form, 40 and to provide an easy adjustment of the side die or guide holding frame both vertically and laterally of the mill.

In the accompanying drawings Figure 1 is a plan view of the forming mill of the

present invention; Figure 2 is a front elevation of the mill, that is an elevation of the side opposite to that on which the driving connections are disposed; Figure 3 is a rear elevation of one of the units of the forming mill; Figure 4 is a cross sectional view 50 through one of the units on the line 4-4 Fig. 3; Figure 5 is a horizontal sectional view through the unit on the line 5-5 of Fig. 3; Figure 6 is a detail plan view of the immediate driving connections for the spindles of the unit; Figure 7 is a detail elevation of the structure shown in Figure 6; Figure 8 is a detail rear elevation of a single spindle stand, showing the adjusting means 55 for the side guide or die frame; and Figure 9 is a vertical sectional view on the line 9-9 of Fig. 8.

As shown in Figures 1 and 2, a plurality of forming mill units A are mounted on a common base or table 1. Each of the units 70 comprises a rear housing formed of two U-shaped stands 2, and a front housing 3 comprising two U-shaped stands 4, which may be interconnected by any suitable members such as a bolted saddle 3^a, and bolted bracket 60 3^b. Bearings 5 and 6 for the upper spindles 7 and lower spindles 8 are supported by the front and rear stands of the unit.

75 All the spindles of a complete machine are driven from a line shaft 9, actuated by 80 suitable means, such as an electric motor 10. At the rear of each unit is a casing 11, which is secured to the stands forming the rear housing of the unit, and which contains 85 the immediate driving connections for the spindles of that unit. Such immediate driving connections comprise a unit driving shaft 12, which carries a worm gear 13 meshing with a worm 14 on the line shaft 9.

90 The unit driving shaft 12 carries a double helical gear 15, with the outer section of which mesh the driving gears 16 and 17 for the two lower spindles 8.

95 With the inner section of the double helical gear 15 mesh idler pinions 18 and 19, which in turn mesh with driving gears 20 and 21 for the upper spindles 7.

Bearings 5 are vertically adjustable by

means of adjusting screws 22, which are shown as of usual form. In order that the centers of the idler gears 18 and 19 and upper spindle gears 20 and 21 may be aligned irrespective of the adjustment of the upper spindles, special mounting means are provided for the idlers. Such mounting means comprise brackets 23 and 24, which are free on the unit drive shaft 12. These brackets provide bearings for the shafts 25 of the idlers 18 and 19. On shafts 25 are links 26 and 27, which are secured to the extremities of the spindles 7.

The idler mounting arrangement provides for the adjustment of the upper spindles without affecting the relative centers of their driving gears. The use of the double helical gear permits the gears for the upper and lower spindles to be identical in structure, so that they are interchangeable in the unit.

With the helical gear arrangement as shown and described, the driving thrust is in opposite directions on the lower spindles 8 and upper spindles 7. The upper pinions 20 and 21, and upper spindles 7, are held against outward thrust by the links 23 and 24 and the links 26 and 27. The direction of rotation of the gear 15 should therefore be clockwise, so that an inward thrust is exerted on the lower pinions 16 and 17 and lower spindles 8. Unmeshing of the gears or undesired horizontal movement of the spindles is thus prevented by the linkage in the case of the upper spindles and by the inwardly directed driving thrust in the case of the lower spindles. There are therefore no locking means between the rolls and front stands to be unfastened as a preliminary step in moving the front stands 4 toward and from rear stands 2.

In order to prepare a unit for the particular work to be done, it is merely necessary to loosen bolts 30 in a cover plate 4^a and slide the housings 4 completely off the table 1. The dies are then slid onto the spindles 7 and 8 and the front housings replaced. In replacing a front housing a stand 4 slides rearwardly of the spindles on the guide strips 29, and is locked in proper position with respect to the dies by means of fastening bolts 30. In each unit the front housing, comprising the two stands 4, may be adjusted as a whole, or the stands may be adjusted one at a time by loosening bolts 33 in bracket 3^b, and saddle bolts 33^a which secure the stands to a saddle 3^a.

This simple manner of applying the dies to the spindles, and adjusting the front housing with respect to the rear housing and dies, avoids any necessity for the use of spacing collars or other spacing means, and greatly facilitates the preparation of the machine for use in making the particular form which is desired.

It will be noted that there is a space 34

between each of the stands of the entire machine. This space may be occupied by a frame 35 for carrying side dies, guides, or rolls, these guide frames may be interposed throughout the entire length of the machine, or only at points where a guide or side forming action is particularly desirable in view of the work to be done.

Each of the guide frames 35 is vertically adjustable by means of adjusting screws 36, which engage in the brackets 3^b between stands 2 and 4, and which support the frame 35 by engagement with the upper portion 37 of the frame. The side die or guide holders 38 and 39 are slidable in ways 40 in the frame 35, and are shown in Figure 9 as carrying side roll shafts 41. The rear guide holder 38 has therein threaded orifices engaging threaded rods or shafts 42. These shafts are rotated by means of pinions 43 meshing with a gear 44 on a hub 45 which carries a hand wheel 46. Interiorly of the hub 45 is an internally threaded sleeve 47 in which engages a threaded rod 48. This threaded rod 48 is connected with the front guide holder 39, and is provided with an individual hand wheel 49.

To adjust the guides for the desired work, the frame is adjusted vertically between the stands by means of the adjusting screws 36. Either or both of the guide holders 38 and 39 may then be laterally adjusted by means of one or both of the hand wheels 46 and 49.

To summarize the advantages of the machine; the unit construction renders it an easy matter to increase or decrease the effective length of the machine as a whole. The special helical gear arrangement for each unit drive renders the driving gears for the spindles interchangeable, and avoids the necessity for any retaining means between the spindles themselves and their bearings in the front housing of the unit. The lateral adjustment of the front housings avoids the use of spacing collars or other spacing means, and this adjustment is facilitated by the absence of any retaining means between the spindles and the front housings. The guide frames are adjustable vertically without changing the position of the front housings, and the position of the guide frames need not be changed because of lateral adjustment of the housings. The guide frames themselves are so arranged that either or both of the guide and die holders therein may be accurately and independently adjusted.

These special advantages all cooperate in securing the general advantage of rendering a change of dies, and adjustment of the machine to a changed class of work, both simple and rapid.

A further advantage of the helical gear arrangement is that the speed of the rolls may be accurately timed since there is no

play due to absence of back lash. This is of great advantage where the dies carried by a pair of opposed upper and lower rolls are not identical but cooperate with each other in a certain definite manner to effect indentation of the stock in the forming operation.

What I claim is:

1. In a forming mill the combination of a base, a pair of housings on said base, a pair of spindles in said housings, a line shaft, a driving shaft connected with said line shaft, a double helical gear on said driving shaft, a gear on one spindle meshing with one section of the double helical gear, and gear connections for the other spindle comprising a member meshing with the other section of the double helical gear. 10
2. In a forming mill the combination of a base, a pair of housings on said base, one of said housings being slidably mounted for movement transversely of the base, a pair of spindles in said housings, a line shaft, a driving shaft connected with said line shaft, a double helical gear on said driving shaft, a gear on one spindle meshing with one section of the double helical gear, and gear connections for the other spindle comprising a member meshing with the other section of the double helical gear. 20
3. In a forming mill the combination of a base, a pair of housings on said base, a pair of spindles in said housings, a line shaft, a driving shaft connected with said line shaft, a double helical gear on said driving shaft, a gear on one spindle meshing with one section of the double helical gear, a bracket freely mounted on the driving shaft, a shaft in said bracket, a link connecting said shaft with the other spindle, an idler gear on said bracket shaft and meshing with the driving gear, a gear on the spindle meshing with said idler gear, guide frames mounted between spindle stands and adjustable vertically thereof, and guide holders independently adjustable in said frames. 30
4. In a forming mill the combination of a base, a plurality of spindle stands providing front and rear spindle housings on said base, the front spindle housings being slidably mounted on the base for movement laterally thereof, and guide frames mounted between spindle stands and adjustable vertically therein. 40
5. In a forming mill the combination of a base, a plurality of spindle stands providing front and rear spindle housings on said base, the front spindle housings being slidably mounted on said base for movement laterally thereof, guide frames mounted between spindle stands and adjustable vertically 50
6. In a forming mill the combination of a base, a plurality of spindle stands providing front and rear spindle housings on said base, the front spindle housings being slidably 60
7. In a forming mill the combination of a base, a plurality of spindle stands providing front and rear housings on said base, a pair of spindles in each pair of said stands, a line shaft, a driving shaft connected with said line shaft, a double helical gear on said driving shaft, a gear on one spindle meshing with one section of the double helical gear, a bracket freely mounted on the driving shaft, a shaft in said bracket, a link connecting said shaft with the other spindle, an idler gear on said bracket shaft and meshing with the driving gear, a gear on the spindle meshing with said idler gear, guide frames mounted between spindle stands and adjustable vertically thereof, and guide holders independently adjustable in said frames. 70
8. In a forming mill the combination of a base, a plurality of spindle stands providing front and rear housings on said base, a pair of spindles in each pair of said stands, a line shaft, a driving shaft connected with said line shaft, a double helical gear on said driving shaft, a gear on one spindle meshing with one section of the double helical gear, gear connections for the other spindle comprising a member meshing with the other section of the double helical gear, guide frames mounted between spindle stands and adjustable vertically thereof, and guide holders independently adjustable in said frames. 80
9. In a forming mill the combination of a base, a plurality of spindle stands providing front and rear housings on said base, a pair of spindles in each pair of said stands, a line shaft, a driving shaft connected with said line shaft, a double helical gear on said driving shaft, a gear on one spindle meshing with one section of the double helical gear, gear connections for the other spindle comprising a member meshing with the other section of the double helical gear, guide frames mounted between spindle stands and adjustable vertically thereof, and guide holders independently adjustable in said frames. 90
10. A guide frame construction for a rolling mill comprising a supporting bracket, frame members having longitudinal ways therein, a guide holder adjustable in said ways, a pair of adjusting screws having a threaded engagement with said guide holder, a second guide holder adjustable in said ways, and a single adjusting screw connected with said second guide holder and arranged for longitudinal movement therewith. 100

11. A guide frame construction for a rolling mill comprising a supporting bracket, frame members having longitudinal ways therein, a guide holder adjustable in said ways, a pair of adjusting screws, a hub in said frame, gear connections with said hub for actuating said adjusting screws, a second

guide holder adjustable in said ways, and an adjusting screw having a threaded engagement in the hub for adjusting the position of said second guide holder.

In witness whereof, I hereunto set my hand.

THEODORE A. SCHRAISHUHN.
